G. P. RASCK

THRESHOLD WEATHER STRIP

Filed Oct. 31, 1921

Fig. 2.

INVENTOR:
George P. Rasck
135 Filaslebwerk
St. Louis

UNITED STATES PATENT OFFICE.

GEORGE P. RASCK, OF DES MOINES, IOWA.

THRESHOLD WEATHER STRIP.

Application filed October 31, 1921. Serial No. 511,731.

To all whom it may concern:

Be it known that I, GEORGE P. RASCK, a citizen of the United States of America, and resident of Des Moines, Polk County, 5 Iowa, have invented a new and useful Threshold Weather Strip, of which the following is a specification.

An object of this invention is to provide an improved weather-strip adapted to be 10 attached to the lower marginal portion of a hinged door and to be pressed into close sealing engagement with the threshold when the door is closed.

A further object of this invention is to 15 provide an improved threshold weather-strip for hinged doors adapted to engage guides on the door casing and be forced by said guides into sealing engagement with the threshold as the door is closed.

20 My invention consists in the construction, arrangement and combination of elements hereinafter set forth, pointed out in my claims and illustrated by the accompanying drawing, in which—

25 Figure 1 is a perspective view showing a portion of a door casing and door equipped with my improvement. Figure 2 is an end elevation of the weather-strip attached to a door, shown in two different positions, the 30 threshold being shown in cross-section.

In the construction and mounting of the device as shown the numerals 10, 11 designate jambs of a door casing, 12 a door hinged to the jamb 11 and adapted to close 35 against stops 13, 14, and the numeral 15 is a threshold, all of which may be of any suitable type and construction, and are here shown conventionally.

30 A strip 16, of suitable sheet metal and of a length corresponding substantially to the width of the door, is fixed to the lower portion of the door, as by screws 17 in a horizontal row, and is mounted on that face of the door which contacts the stops 13, 14. 45 The screws 17 are arranged along the upper margin of the strip 16 and are spaced from the lower margin of the door a suitable distance to permit the action of the strip hereinafter explained. The strip 16 is formed 50 at its lower margin with a recurved loop 18 extending from end to end thereof, projecting away from the door in substantially a horizontal plane near the lower margin of the door, and having its opening directed

toward the door. The strip 16, is also 55 formed with a rib or angular bead 19 extending from end to end thereof and spaced a short distance below the row of fasteners 17, and said rib or bead is so formed that the tendency of the main portion of said strip, below said bead or rib, is to stand 60 away from the door 12 in an inclined plane, substantially as indicated by dotted lines in Figure 2. A compression strip 20, formed of rubber or other suitable material, 65 is provided and is T-shaped in cross-section and has its leg flange received within and extending from end to end of the recurve loop 18 of the metal strip. The loop 18 may be formed with dents or depressions 21 at 70 intervals to retain the compression strip in place. The head of the T-shaped compression strip 20 lies in a plane just behind the metal strip 16, and is adapted at times to contact with the adjacent face of the door 75 12 along its lower margin; and said head is also adapted to contact, at its lower margin, with the upper face of the threshold 15, as shown by solid lines in Figure 2, thereby 80 effectually closing and sealing any crack which might otherwise exist between the lower margin of the door and the threshold. Curved guides 22, 23 are fixed to lower end 85 portions of the stops 13, 14 or jamb members and project outwardly from the faces thereof just above the threshold 15.

The lower faces of the guides 22, 23 are of convex curvature and are so arranged that, in the process of closing the door, they are engaged by the outer edge of the recurved flange or loop 18, and continued closing movement of the door causes said loop, and with it the lower portion of the metallic strip to be pressed toward the adjacent face of the door. Such movement also ex- 95 erts a downward pressure on the loop 18 and compression strip 20, and when the door has arrived at its fully closed position such pressure causes the compression strip to form a seal for the joint between the lower 100 margin of the door and upper face of the threshold which excludes all drafts as well as moisture from without. The guides 22, 23 not only serve to guide the loop and compression strip to their sealing position, but 105 hold them in such position so long as the door is closed, as shown clearly by the solid lines in Figure 2, the metal strip, recurved

loop and compression strip being under tension at such time, and the bead or rib 19 of the metal strip serving as an offsetting means and also as an integral hinge permitting the necessary flexing of the strip.

I claim as my invention—

1. The combination with a door casing, door and threshold, of a weather-strip comprising a metallic strip secured at its upper margin to the lower portion of said door, said metallic strip being resilient and normally standing at an angle away from the door, said metallic strip being formed at its lower margin with a recurved loop opening toward the door, a compression strip substantially T-shaped in cross-section having its leg flange mounted in said loop and its head directed toward the door, and curved guides carried by the door casing and adapted to be engaged by end portions of said loop when the door is closed, and said guides being so curved and the weatherstrip so positioned on the door that the head of the compression strip is forced against the door

and also against the threshold when the door is closed.

2. In a weather-strip, a resilient metallic strip adapted to be secured at one margin to the outer face of a door transversely of the lower portion thereof, said metallic strip being formed with a longitudinal bead or rib adjacent its upper margin forming an integral hinge, said metallic strip also being formed with a recurved loop at its lower margin opening toward the outer face of the door, and a compression strip of flexible and compressible material, formed substantially T-shaped in cross-section and having one flange projecting and secured within said recurved loop, the head of said compression strip being adapted to engage at times with the outer face of the door and extend below the edge thereof whereby it also is adapted to engage a threshold below said door.

Signed at Des Moines, in the county of Polk and State of Iowa, this 22d day of September, 1921.

GEORGE P. RASCK.
